UNITED STATES PATENT OFFICE.

HENRY L. LEWEN, OF NEW YORK, N. Y.

FLOOR AND CEILING CONSTRUCTION.

1,014,157.

Specification of Letters Patent.

Patented Jan. 9, 1912.

Application filed July 12, 1911. Serial No. 638,085.

To all whom it may concern:

Be it known that I, HENRY L. LEWEN, a citizen of the United States, residing at New York, in the county of New York and 5 State of New York, have invented certain new and useful Improvements in Floor and Ceiling Construction, of which the following is a specification.

My invention relates to certain new and 10 useful improvements in fire-proof floor and ceiling construction and to a novel construction and arrangement of reinforcing elements by which the desired objects may be attained; and the invention consists of the 15 parts, and the constructions, arrangements and combinations of parts which I will hereinafter describe and claim.

In the accompanying drawings forming 20 part of this specification and in which similar reference characters indicate like parts in the several views, Figure 1 is a perspective view partly broken away, of a floor and ceiling construction embodying the 25 salient feature of my invention. Fig. 2 is a similar view showing a reinforcing element of slightly modified form. Fig. 3 is a similar view showing the application to the reinforcing element of a transverse clip arrangement. Fig. 4 illustrates a sectional detail of a concrete floor and hanging ceiling showing reinforcing clip extending between the same, and engaged by tension rods. Fig. 30 5 is a clip of slightly modified form. Fig. 6 illustrates a ribbed reinforcing element 35 and clip, said element being provided with a supplemental hollow rib to receive a fire-proof ceiling board. Fig. 7 is a modified form of supplemental hollow rib. Fig. 8 is a perspective view of a clip for fastening the 40 ribbed sheets together, showing a reinforcing means.

In carrying out my invention I prefer to use the same in connection with an I-beam, A, or other supporting member upon which 45 the main reinforcing element, 3, may be supported in any of the ways hereinafter mentioned, or in any desired manner. The reinforcing element, 3, is preferably in the form of a sheet-metal plate rolled or otherwise 50 provided with hollow ribs, 4, which are made to project at right-angles from one side of the plate and which ribs are arranged in parallel order and are connected by an intervening substantially straight flat portion, 55 5, in a manner substantially as disclosed in my former application, Ser. No. 571,743,

filed July 13, 1910. This reinforcing element differs, however, from the like element of the aforesaid application in that the plain portions, 5, of the plate which lie intermediate of the hollow ribs, 4, is provided with slots, 6, formed by slitting portions of the plate at two opposite points and bending the slitted portions outwardly, as shown at 7; the slits may extend lengthwise of the plate and they may be arranged in rows parallel with the ribs, 4, or they may be otherwise arranged without departing from the spirit of the invention. The slits may, also, extend transversely of the portion of the 60 plate between adjacent parallel ribs or said slits may extend both longitudinally and transversely, as clearly shown in the present drawings. Whatever the arrangement 65 and character of the slits, the essential feature is the expanding or bending out of the portion formed by the slits so as to form lower projections on the plate adapted to serve as binding means for the engagement of the plaster which is to form the ceiling of the structure.

My present invention comprehends the incasing of the I-beam, or other support, in concrete and to this end I provide a reinforcing element which extends from the aforesaid plates downwardly and under the I-beam, the arrangement being such that open spaces, 9, are left at the top into which the concrete may be placed to thereby embed the aforesaid beam. 90

In Fig. 1 I show an arrangement wherein the longitudinal hollow ribs, 4, are arranged parallel with each other and the portions of the plates adjacent the I-beam are slitted at the bases of the ribs so that the ribs may extend over or bridge the space, 9, and rest on the top flange of the beam; the slitted portions are bent downwardly at 8, and these bent portions are also slitted in the manner before described, and are extended under the lower flange of the beam, and secured in some appropriate manner. In Fig. 1 the construction includes the slitting of plates upon each side of the I-beam and the bending of the slitted portions down along the sides of the beam and under said beam, the meeting edges of the plates being brought together below the lower flange of the I-beam and being seamed together as shown at 10. By the construction disclosed 100 the open spaces, 9, are left at the top between adjacent ribs and into these spaces 105 110

the wet concrete may be readily poured. The bent portions of the plates thus form housings or molds for retaining the cement which embeds the beam, while the plates are supported in a substantial manner by reason of their hollow ribs extending over the upper flange of the beam and overlapping each other, as clearly indicated.

After the plates are assembled in the manner shown and described, the concrete, 12, for the floor slabs is added and the ribs and plates become embedded and thereby form a metal reinforce for the ceiling or floor construction. If desired suitable sleepers, 13, may be embedded in the surface of the concrete floor slabs upon which sleepers the usual flooring, 14, may be nailed or otherwise secured.

If preferred, the portion of the reinforcing element which extends downwardly along the sides and beneath the I-beam may have hollow ribs, 15, extending from both sides of the plate; in other words, a ribbed construction of the type shown in my former Patent No. 986,474, March 14/11, may be employed. In this instance the part of the element, 16, which incases the lower part of the I-beam may be made separate from the reinforcing plates, 3, before mentioned and may have its edges interlocked or suitably connected to the corresponding edges of the first mentioned reinforcing plate, as shown at 17, in Fig. 2. In this figure, it will also be seen that the hollow reinforcing ribs, 4, of the main plates do not extend over the top flange of the I-beam, but project under said flange and this may be effected without departure from my invention; in which case, also, the openings 35 are left at the top between the hollow ribs for the admission of the concrete material.

In the construction shown in Fig. 2 I may also find it desirable to employ the interlaced tension wires, 18, which pass through openings in the apices of the ribs, 17, and which ribs extend lengthwise of the plate and accordingly lengthwise of the I-beam and at right-angles to the ribs of the first-mentioned plates, 3. When employing the tension wires, 17, as in Fig. 2, I also prefer to use tension rods, 19, which extend lengthwise of and between the hollow ribs, 3, of the first-mentioned plate, the inner ends of these tension rods hooking over the top flange of the I-beam, said tension rods serving as supports for the tension wires, whereby the separate ribbed plate, 16, which incases the lower portion of the I-beam may be supported in position from the 60 tension ribs.

When using the construction shown in Fig. 2, the ribbed plate, 16, which incases the lower portion of the I-beam may not be slotted with portions bent outwardly as in Fig. 1, as the double-ribbed arrangement of

the plate will provide keys on the outer surface for the plastering, which may be placed over the outside of the plate to thereby form a finish for the ceiling. In either of the constructions shown it will be apparent that a plank may be placed across the top of the hollow ribs to be used as a scaffold for workmen to carry the wet mixture for pouring into the openings formed between the inner ends of the ribs, to embed 70 the I-beam and form a fire-protection. 75

The construction shown in Fig. 2 with its additional tension rods, 19, is especially designed for large spans as the rods will act as tension members, as also the ribs, and will help the compression members. The dimensions of these tension rods, 19, will depend upon the span and the live-load of the floor slabs, as will be indicated by tables of information usually supplied and which are 80 familiar to those skilled in this art. 85

The slotted portions of the main plates and the bending outwardly of the portions, 7, between the slits may be so arranged that the concrete will not pass entirely through the slots thus formed, accordingly there will remain projections on the outer surface of the plate for a binding for the plastering which is to form the ceiling of the proposed structure, this being a leading feature of my 90 invention. 95

In Fig. 3, I show in connection with the perforated and ribbed plates before mentioned a novel form of clip, 20, consisting of a strip which extends across the upper portion of the plates, said strips being bent into arched form, as in Figs. 3 and 6, and slotted longitudinally at the top and bottom and with the slotted portions bent in opposite directions. The slotted portions at the 100 bottom of the clip form forks, 21, which are made to straddle the upper portion of the hollow ribs, and the slotted portions at the top of the clip have their ends welded at 20' or otherwise rigidly connected in line 110 to make a continuous reinforcement, said clips being designed to be embedded in the concrete floor slabs in the same manner that the hollow ribs are embedded. The clips are spaced apart at certain intervals, say 115 from six to twelve inches apart so as to give additional reinforcement for the concrete floor slabs, and to act as tension members and to be fastened to the tension rods, 19, in any manner which may seem best for the 120 purpose.

In each of the instances heretofore mentioned I have disclosed a building element with a hollow ribbed surface of the general type disclosed in my prior application; I may, however, fashion this plate with a further rib or ribs of a special form as shown at 22, in Fig. 6, this additional rib projecting from one side of the plate say 125 from the side opposite to that containing 130

the hollow ribs, 4, and said additional rib, 22, being provided with grooves in its sides adapted to receive edgewise a fire-proof board, 23, which is designed to form a ceiling; this board because of the projection of the hollow additional rib, 22, is held spaced from the ribbed element, 3, a sufficient distance to form an air-chamber between the fire-proof board and said element. The additional hollow rib may have its outer grooved portion integral with the rib, to form a molding, 24, or, if desired, the rib may be used in association with a separate molding, 25, which will be secured to the rib by means of a screw, 28, or other fastening, as shown in Fig. 7. In either instance the fire-proof boards have their adjacent edges fitted in the grooves of this special hollow rib and the space between the boards and the main ribbed element forms an air chamber as before described. The separate molding, 25, or the corresponding integral molding, 24, of the hollow rib, as well as the hollow rib itself, may be filled at the same time that the slab is formed, by introducing the concrete through the openings formed between the ribs of the main plates as before mentioned. These parts may be filled first with a special asbestos composition so as to enable the thread of the screw, 28, to enter the composition.

The clip construction shown in Figs. 4 and 5 is designed particularly for use in connection with upper and lower reinforcing elements in the form of plates with projecting hollow ribs, as illustrated in Fig. 4. In this figure one of the reinforcing elements, 3, has its ribs embedded in the concrete floor, while the other reinforcing element, 3', is suspended a suitable distance from the first member and has the hollow ribs projecting from its inner surface. Between the ribs of the two reinforcing elements, 3, 3', extends the clip, 30, which clip is composed of a sheet of metal having its ends split and bent in opposite directions and made to substantially conform to the cross sectional character of the rib. The split or forked end of the clip may enter the hollow rib of the upper reinforcing element, 3, as shown in Fig. 4, while the split or forked lower end of the clip may be made to pass around the outside of or straddle the rib of the lower reinforcing element, 3'. If desired, the split or forked opposite ends of the clip may pass upon the outside of the ribs of both the upper and reinforcing elements, as shown in Fig. 5, but in any event the split ends of the plate will be bent to substantially conform to the cross sectional shape of the head of the rib. The clips are placed in parallel order at suitable distances apart and have their central portions slit and bent to form an eye through which passes a tension rod, 31, and which rod may be fastened to an I-

beam or anchored into the walls. In practice the top building element, 3, is generally supported on the wall or on an I-beam to form a concrete floor slab, while the lower plate or building element, 3', is substantially parallel with and extends in the same direction as the plate, 3, and is connected to the latter by the clip, 31, before mentioned, which clip has the perforation for the tension rod, 31, before mentioned. The clip, 20, Fig. 3, acts as an additional reinforcement for the floor slab and its ends are welded sidewise to an adjoining clip and the extremities of these welded portions will be bent in opposite directions to form the forks adapted to engage and anchor onto the hollow rib before mentioned. The clip, 30, will also be found desirable for fastening the two ribbed sheets together to form a mold for the wet concrete, for wall construction or for columns or piers, but it is especially useful for the hanging ceiling construction before mentioned and as shown in Fig. 4.

Having thus described my invention what I claim as new and desire to secure by Letters Patent is:—

1. In a ceiling and floor construction, a building element comprising a metal plate with projecting ribs running lengthwise thereof, said plate being slotted adjacent the bases of the ribs and the slotted portions bent to one side so as to leave the ribs projecting beyond the bent portion of the plates.

2. In a ceiling and floor construction, a building element comprising a metal plate with projecting ribs running lengthwise thereof, said plate being slotted adjacent the bases of the ribs and the slotted portions bent to one side so as to leave the ribs projecting beyond the bent portion of the plates, the portion of the plates intermediate of the ribs being slotted with portions offset from the outer surface of the plate to form holding means for plastering.

3. In ceiling and floor construction, the combination with a flanged beam, of a building element comprising a metal plate fashioned with hollow ribs which project from the surface thereof and extend along the plate in parallel order, said plate being slotted from the end inwardly whereby the ribs project and overlap the beam and the slotted portions of the plate may be bent downwardly relatively to the beam, to provide openings for the admission of concrete material, said element being continued over the sides and beneath the beam to form a mold to enable the beam to be embedded in concrete, tension rods engaging the beam and extending substantially parallel with the ribs, and tension wires passing around the mold portion of said element and suspended from said rods.

4. In a ceiling and floor construction, the

combination with a flanged beam, of a building element comprising a metal plate fashioned with hollow ribs which project from the surface thereof and extend along the plate in parallel order, said plate being slitted from the end inwardly whereby the ribs project and overlap the beam and the slitted portions of the plate may be bent downwardly relatively to the beam, to provide openings for the admission of concrete material, said element being continued over the sides and beneath the beam to form a mold to enable the beam to be embedded in concrete, tension rods engaging the beam and extending substantially parallel with the ribs, and tension wires passing around the mold portion of said element and suspended from said rods, said plates being slitted at numerous points intermediate of the ribs with the slitted portions expanded outwardly to form holding means for plastering, and said ribs and tension rods adapted to be embedded in concrete.

5. In a ceiling and floor construction, the combination with a beam of a building element inclosing the lower portion of the beam, said element being fashioned with hollow ribs which project from the surface and said element being slitted in parallel lines to allow portions of the ribs to be bent to one side and to afford open spaces for the reception of concrete by which the beam is embedded, and means suspending the plate from the beam, said plate being slitted intermediate of the ribs with the slitted portions expanded outwardly to form binding means for the reception of plastering.

6. A building element comprising a metal plate fashioned with projecting ribs running lengthwise of the plate and extending from the surface thereof, said plate being slitted at points intermediate of the ribs and the slitted portions expanded outwardly to form binding means for an exterior coating of plaster, said ribs projecting beyond the plate at the end and adapted to be embedded in concrete, and a support for the projecting ends of the ribs.

7. In ceiling and floor construction, the combination with a supporting beam, of a building element comprising a sheet metal

plate having ribs projecting from the surface said ribs projecting beyond the plate at the end and said plate being bent to pass around and inclose the sides and bottom of the beam to thereby form a mold for material admitted through openings at the top between the beam and bent portion of the plate, and means suspending the plate from the beam.

8. In a floor construction, the combination with a supporting beam, of a building element comprising a sheet metal plate fashioned with hollow ribs which project from the surface thereof, said plate being slitted from the end inwardly and the slitted portions bent to one side to allow the ribs to project and to form openings at the top for the admission of concrete, and a clip formed of a strip of metal slitted longitudinally and with the slitted portions bent in opposite directions and fashioned to substantially conform to the cross section of the ribs and adapted to straddle said ribs, said clip and ribs adapted to be embedded in concrete.

9. In a floor construction, the combination with a supporting beam, of a building element comprising a sheet metal plate fashioned with hollow ribs which project from the surface thereof, said plate being slitted from the end inwardly and the slitted portions bent to one side to allow the ribs to project and to form openings at the top for the admission of concrete, a clip formed of a strip of metal slitted longitudinally and with the slitted portions bent in opposite directions and fashioned to substantially conform to the cross section of the ribs and adapted to straddle said ribs, said clip and ribs adapted to be embedded in concrete, tension rods extending substantially parallel with the ribs and having hooked ends to engage the beam, and tension wires engaging the rods and passing around the bent portion of said elements and said beam.

In testimony whereof I affix my signature in presence of two witnesses.

HENRY L. LEWEN.
